SPARK PLUG

Frederick A. Ost, Los Angeles, Calif.

Application June 10, 1940, Serial No. 339,647

9 Claims. (Cl. 123—169)

This invention relates to spark plugs and more particularly although not exclusively to that type which is adapted for dependable and economical use on aeroplane engines. A common source of trouble with spark plugs results from a coat of carbon deposited between or in proximity to the spark gap. This carbon deposit tends to form a pathway for the current that is of much less electrical resistance than the gap jump. Since electricity follows the path of least resistance, the current takes this path over the carbon, delivering part or all of the current away from the gap. This results in a weakened spark or no spark at all with consequent loss of power, rapid accumulation of carbon and complete failure of the functioning of the parts of the engine. Another source of trouble with spark plugs results from leaking of water around the plug or through the parts of the plug, this being particularly true in cold and wet weather. With spark plugs, especially in connection with those used on aeroplane engines which are air cooled it has been found that in most instances the relatively high temperatures of the engine, results in the insulation which is employed breaking down. Further it has been found that breakage of plugs of standard design occurs frequently, and especially when the terminals thereof are accidentally struck by a tool during installation or adjustment. By the use of my invention the above objections are overcome or materially reduced.

Among further advantages attained by my invention may be mentioned the following:

1. A spark plug that assures a clean spark plug and delivery of all of the current to the spark gap at all times, thus resulting in a fat spark as the current jumps across the spark gap and assurance against a foul plug.

2. A spark plug in which the gas mixture is brought into contact with the spark gap terminals in such manner as to automatically clean or scavenge the terminals and contact the spark so as to immediately ignite said mixture.

3. A spark plug which will withstand extremes of heat and cold without cracking, breaking or leaking gas.

4. A substantially unbreakable and indestructible spark plug which has a maximum of efficiency, coupled with long lasting qualities.

5. The complete suppression of leakage which prevents irregular operation of an engine and prevents static in radio sets used in aeroplanes.

6. A spark plug that permits of quick and easy dismantling of parts for quickly inspecting

and cleaning and which assures quick and positive reassembling of parts by skilled or unskilled labor in an effective manner and with gas tight joints without breaking.

5 To these ends my invention comprises the features of construction and combination of parts hereinafter described and claimed.

In the drawing, Fig. 1 is a vertical section of my improved spark plug in which the insulating plug is shown in full side elevation; Fig. 2 is a side elevation of the plug removed from the shell, part being broken away and in section; Fig. 3 is an end plan of the plug; Fig. 4 is a plan of the stamping from which the outer spark gap terminal is formed; Fig. 5 is a plan of the circular abutment ring; Fig. 6 is a section of a detail taken on line 6—6 of Fig. 5; Fig. 7 is a plan of the split abutment ring; Fig. 8 is a section of a detail on line 8—8 of Fig. 7; and Fig. 9 is a vertical section of a portion of a spark plug showing a modified form of my invention.

In the drawing A indicates the metallic shell of my improved spark plug which is externally threaded at 10 on its inner end to screw into the usual threaded spark plug hole in the wall of the combustion chamber of an internal combustion engine and which is externally shouldered on its outer end at 11 for engagement by a wrench to assist in screwing and tightening the plug in the cylinder wall. Internally the body of the shell is passaged longitudinally at 13, the outer end being longer in diameter than the inner portion and internally threaded at 14 for engagement by the external threads 15 of a bushing B, to be hereinafter described. The passage 13 tapers from the inner end of the plug towards its outer end to form a seat for the insulating core C as will be hereinafter described.

The insulating core C consists of a tubular body 16 made out of insulating material such as pressed mica or other suitable material having a conical inner end 17, the outer conical surface of which corresponds with the inner conical surface 13 of the shell upon which it is adapted to seat tightly. A metal spindle 18 extends longitudinally and axially through the insulating core and has a circular spark gap terminal head 19 on its inner end and a nut terminal head 20 on its outer end by which it is secured tightly in the insulating core. The circular head is dished to form an annular rim 21 which functions as one electric terminal of the spark gap. The insulating core C is drawn tightly upon its seat in the metallic shell A by turning the bushing B into the shell, an annular abutment 22 and a

split abutment collar 23 being interposed between and engaging the bushing and insulating core. The abutment ring is formed with a beveled inner face 24 facing forwardly towards the outer end of the spark plug. The split abutment collar is in two halves spaced circumferentially slightly apart and engages the insulating core against a shoulder formed by an annular recess 25 in the insulating core and has an outer circumferential inwardly beveled end 26 pointed inwardly and engaging the corresponding beveled surface of the annular abutment ring 22. Thus by screwing the bushing outwardly the core is tightened upon its seat to produce a leak-proof joint between the insulating core and the shell. By screwing the bushing inwardly the split abutment collar can be removed by lifting its segments out of the annular groove 25, thus releasing the insulating core and permitting its removal from the shell.

The opposed electric terminal D, which operates with terminal 19 in producing the spark gap is formed from a stamping (see Fig. 4) resembling a cage having a ring 28 and radiating arms 29, the latter having shoes 30 on their outer ends concentric with the center of the ring. These arms 29 are bent upwardly above, outwardly and down with their shoes engaging in detentures 31 in the side wall of the inner end of the insulating plug. The ends of the arms 29 and shoes 30 are held tightly impressed by the insulating core C in close contact with the inner wall of the passage 13 in shell A to produce electrical connection with the shell, the latter forming one of the electrical terminals by contact with the wall of the engine cylinder in the usual manner. The opposite external electrical terminal is adapted to be made with the outer threaded end of the spindle 18 in the usual manner. Normally the terminal ring 28 is spaced slightly and evenly above the annular shoulder 21 on the terminal head 19 so that upon becoming energized a fat spark is produced between the terminals thus formed without carbon collecting to reduce the efficiency of the discharge. The central opening in ring 28 of the spark gap terminal and the dished head which forms the annular rim 21 of the companion spark gap terminal producing a passage by which the gas mixture enters and mushrooms radially through the spark gap and automatically scavenges the spark terminals, thereby providing a fresh and immediate contact of gas mixture in the gap for ignition and preventing fouling of the spark gap terminals. This is extremely important for it increases the effectiveness of ignition. Also the spark gap terminal ring 28 and companion terminal head 19 project beyond the spark plug shell A, thus affording a better exposure of the spark in a position wherein the gas mixture has immediate contact with the spark. The terminal head 19 and terminal ring 28 afford a large surface exposure which increases the likelihood of the production of an effective spark without any danger from interrupted ignition. The dished terminal head also has an annular groove 19 in its side wall which tends to produce an inward, upward and outward eddy of the gas mixture to additionally scavenge the spark gap terminals and prevent fouling. The spark plug can be easily dismantled by screwing the bushing inwardly, removing the split collar 23 and sliding the insulating core C out of the shell. When thus removed the terminal D can be removed by springing the shoes 30 out from engagement with

the insulating plug and a new replacement made or the parts can be cleaned. The abutment rings which are connected by conical shoulders and loosely seated permit the self-centering of the core so that the conical shoulders between the core and shell seat closely when drawn tightly by the bushing.

In the construction shown in Fig. 9, the insulating core E is shown seated in the shell F by the inward thrust of the threaded bushing G instead of by the outward pull as shown in Fig. 1 and the spark gap terminal cage H, similar to terminal D, is engaged with the wall of the shell as in the preferred construction and the inner tapering end of the insulating core E engages the shoes by a wedging action and holds the arms pressed outwardly to produce close electrical connection with the shell and hold the terminal I rigidly spaced at suitable interval from the spark terminal H to produce an effective spark gap.

Where I have used the terms "ring" or "annulus" in the above description and claims following, as applied to the part 28 of terminal D, I mean to include any suitable shape constituting a band containing an inner opening through which gases may circulate for scavenging the spark gap terminals or more effectively contacting the fuel mixture with the ignition spark.

In accordance with the patent statutes, I have described the principles of operation of my invention together with the construction thereof which I now consider to represent the best embodiment thereof but I desire to have it understood that the structure shown is only illustrative and that the invention can be carried out by other means and applied to uses other than those above set forth within the scope of the following claims.

I claim:

1. A spark plug, comprising, an outer electric conducting shell having an inner longitudinal tapering shoulder, an insulating core having a corresponding outer tapering shoulder adapted to seat against said inner tapering shoulder, a bushing threaded in said shell adapted to force said core longitudinally with its tapering shoulder seated tightly against the tapering shoulder of said shell, a conducting spindle extending longitudinally through said core having a spark gap terminal on its inner end, and a terminal cage having an annular spark gap terminal in juxtaposition to said spark gap terminal on said spindle and a support forming an electric conductor extending rearwardly from said annular spark gap terminal and secured in contact between the adjacent surfaces of said conducting shell and said insulating core.

2. In a structure as defined in claim 1, the terminal cage having a plurality of supporting arms extending rearwardly and secured in contact between the adjacent surfaces of said conducting shell and said insulating core.

3. In a structure as defined in claim 1, the terminal cage having a plurality of supporting arms extending inwardly between said shell and insulating core having shoes seated in and engaged with said insulating core and adapted to be clamped in contact between the shell and core when the core is seated in said shell.

4. A spark plug, comprising, an outer electric conducting shell having an inner shoulder tapering inwardly, an insulating core having an outer corresponding shoulder tapering inwardly and adapted to seat tightly upon said inner

shoulder, a bushing screwthreaded in said shell, an abutment element separately mounted upon the outer end of said insulating core with which said bushing is adapted to engage when unscrewed to tightly seat the tapering shoulders of the shell and insulating core, an electrical conducting spindle extending longitudinally through said core having a spark gap terminal on its inner end and a terminal cage having an annular spark gap terminal in juxtaposition to said first spark gap terminal and a supporting member forming an electrical conductor secured to said insulating core, whereby the pair of spark gap terminals are united with said insulating core as a single assemblage, said support being held in electrical contact with said shell by said insulating core.

5. In a structure as defined in claim 4, the abutment element consisting of a segmental ring and the insulating core having an annular groove in which said segmental ring is adapted to be assembled in position to be engaged by the outward screw movement of said bushing to draw the insulating core tightly seated in said shell.

6. In a structure as defined in claim 4, an abutment element comprising two cooperating encircling rings connected by bevels, one of the abutment elements consisting of a segmental ring and the insulating core having an annular groove in which said segmental ring is adapted to be assembled in position to engage said core and the other engaging said shell and adapted to draw the core and shell tightly together by the outward screw movement of said bushing.

7. A spark plug, comprising, an outer electrical conducting shell having an inner longitudinal tapering shoulder, an insulating core having a corresponding outer tapering shoulder adapted to seat against said inner tapering shoulder, a bushing threaded in said shell adapted to force said core longitudinally with its tapering shoulder seated tightly against the tapering shoulder of said shell, a conducting spindle extending longitudinally through said core having a spark gap terminal on its inner end, and a cage having an annular spark gap terminal and a support forming an electrical conductor extending rearwardly therefrom and secured in contact between the adjacent surfaces of said conducting shell and

said insulating core, the spark gap terminal on the inner end of said spindle comprising a dished head in juxtaposition to and spaced from said annular terminal to form a passageway through which gases may circulate and mushroom radially between and scavenge said terminals.

8. A spark plug, comprising, an outer electrical conducting shell having an inner longitudinal tapering shoulder, an insulating core having a corresponding outer tapering shoulder adapted to seat against said inner tapering shoulder, a bushing threaded in said shell adapted to force said core longitudinally with its tapering shoulder seated tightly against the tapering shoulder of said shell, a conducting spindle extending longitudinally through said core having a spark gap terminal on its inner end, and a cage having an annular spark gap terminal and a support forming an electrical conductor extending rearwardly therefrom and secured in contact between the adjacent surfaces of said conducting shell and said insulating core, the spark gap terminal on the inner end of said spindle comprising a head having an annular groove in its side wall and in cooperation with said companion annular terminal tending to produce an inward, upward and outward eddy of the gas to assist in scavenging the spark gap terminals.

9. A spark plug, comprising, an outer electrical conducting shell having an inner seat, an insulating core having a body adapted to close upon said seat, a bushing threaded in said shell adapted to hold said core with its body tightly seated, a central inner electrode extending longitudinally through and provided with a terminal head exposed on the spark gap end of said core and having a concave exposed end and an annular grooved side wall, and an outer terminal cage having a terminal band and means for supporting the band on the inner end of said shell in juxtaposition over the rim of the inner terminal head to provide a central duct through which the gases are mushroomed radially by said concave inner end of the central electrode and are caused to produce an inward, upward and outward eddy by said annular grooved side wall of the central electrode to effectively scavenge the spark gap terminals and prevent fouling.
